(57) **CLAIM**

The ornamental design for a personal protection device, as shown and described.

DESCRIPTION

FIG. 1 is a front, left, top perspective view of a personal protection device of the present invention;

FIG. 2 is the front plan view of FIG. 1, the rear plan view being a mirror image thereof;

FIG. 3 is the left plan view of FIG. 1, the right plan view being a mirror image thereof;

FIG. 4 is the top plan view of FIG. 1; and,

FIG. 5 is the bottom plan view of FIG. 1.

The broken lines shown in the drawings show unclaimed subject matter only and form no part of the claimed design.
